UNITED STATES PATENT OFFICE.

JOHANN MARTIN WEBER, OF FRANKFORT-ON-THE-MAIN, GERMANY, ASSIGNOR TO
ERNST GIDEON BEK, OF PFORZHEIM, GERMANY.

RING-MESH MACHINE.

Application filed October 9, 1923, Serial No. 697,505, and in Germany October 21, 1922.

This invention relates to machines for making ring mesh fabrics. The object of the invention is to provide a simpler and more efficient pattern mechanism for selecting one of two or of a plurality of wires at every formation of a ring of such selected wire.

For this purpose I use a flat or cylindrical pattern plate of electricity conductive material on the surface of which the pattern is applied by coating it with non-conductive material. A contact pin is pressed against the pattern plate surface and a relative motion between said pin and said plate is caused corresponding to the motion of the ring mesh in the machine, when the individual rings are formed and when the ring mesh is shifted after formation of one complete row of rings.

The annexed drawings show the said pattern mechanism which may be applied to any ring mesh machine or more particularly to the device for feeding a wire to the ring forming tools, especially to the knives cutting off the required length of wire.

Fig. 1 is a front view and Fig. 2 a side view of the new mechanism indicating parts of the machine in immediate connection with it.

a is the table of the machine, *b*¹ is a guide block on which the slide *b* is moving lengthwise. The roller *b*³ with pins to hold and shift the mesh fabric is mounted in a frame *b*² resting on the slide *b* and which may be swung backward around the shaft *n* which is rotatably mounted on the slide *b*. *y* and *z* indicate the blocks carrying the tools for forming the rings and for inserting every ring into the neighbouring rings previously formed. Suitable means is provided for intermittently operating the roller *b*³ in predetermined steps after the completion of each series of rings to vertically shift the ring mesh. Provision is similarly made to shift the slide *b* in a stepwise manner to adjust the roller *b*³ in the direction of its length as the formation of the ring mesh proceeds.

m is an arm mounted on the pivot *m*³, which by the action of an electric-magnet *k* and a spring *k*³ may take two positions bearing respectively against the stop screws *k*¹ *k*². In the upper part of the arm *m* two holes or channels *m*¹ *m*² are provided serving as guideways for two wires of different colours. By swinging the arm *m* to the right or left hand, one of the said holes *m*¹

*m*² is brought into registry with the mechanism (not shown) to feed a predetermined length of the wire to the cutting-off knife and the ring forming tools. The mechanism so far described forms no part of the invention and has accordingly been illustrated in diagrammatic form only. The present invention relates entirely to the means for controlling the operation of the arm *m*.

f is the pattern plate of conductive metal having the pattern applied to its upper surface by covering the area of the pattern or design with a nonconductive lacquer. This plate is placed in a carriage *f*¹ provided with rollers *f*² running in guide ways *f*³ of a supporting plate *f*⁴, which is attached by rods *f*⁵ *f*⁶ to the table *a*.

d is a slide guided on a rod *d*¹ fixed to the rods *f*⁵ *f*⁶ in a direction rectangular to the guideways *f*³. *d*² is a contact pin pressed by spring *d*³ against the surface of the pattern plate *f*. *d*⁴ is an electric conduit leading to the electromagnet *k*, which itself is connected by the wire *d*⁵ to the machine frame, the latter being in conductive connection with the lower side of the pattern plate *f*.

Motion is imparted to carriage *f*¹ from the shaft *n*. This shaft is connected with the shaft of roller *b*³ by a link belt *n*¹ to adopt the same motion as roller *b*³ viz, a stepwise rotation after the completion of every series of rings, shifting the ring mesh vertically the distance of two consecutive series of rings. The shaft *n* is provided with a key *n*² and a roller *h* is mounted on it, free to slide in axial direction but rotating together with it. A fork *n*³ mounted on the table *a* prevents roller *h* from participating in the axial motion of shaft *n*, when the slide *b* is fed stepwise at the formation of a ring. The roll *h* has the same diameter as roller *b*³ and has wound on its circumference a string *h*¹. This string runs over guides *h*² *h*³ *h*⁴ to the carriage *f*¹, is fixed thereto and goes on over guide *h*⁵ and carries the weight *h*⁶. Thereby the carriage *f*¹ is moved at every movement of the roller *b*³ the same length in its guideways *f*³ as the ring mesh is moved vertically.

The motion of the slide *d* is caused by a string *c*. This string is attached to the end of shaft *n* or may be attached to any point of the slide *b* and runs over guides *c*¹ *c*² to slide *d*, is attached thereto and runs on over guide *c*³ to carry the weight *c*⁴.

Thereby the shifting stepwise motion of slide b is transmitted to pin d^2 .

The pin d^2 travels in consequence of the two described motions over the whole surface of plate f in parallel lines. Whenever it touches the metallic surface of the plate, the electromagnet k is energized and attracts arm m and whenever it touches the nonconductive coating the arm m returns to its prior position by the action of spring k^1 .

Now what I claim is:

1. In a ring-mesh machine including ring-forming tools and means for feeding the ring-mesh horizontally and vertically in predetermined steps as the formation of the ring-mesh proceeds, the combination of a pattern plate of conductive material, a pattern applied to its surface making it non-conductive for the area of the pattern, a contact pin pressed against the surface of the pattern, means to cause a relative motion between said pin and said pattern plate to correspond with the vertical motion of the ring-mesh after completion of a row of rings and with the horizontal motion at the formation of every ring, a movable guide for a plurality of wires whereby the latter are guided to the ring forming tools and an electric circuit comprising the said contact pin, the said pattern plate and means to actuate the said movable wire guide by closing and breaking the current in the said circuit.
2. In a ring-mesh machine including ring-forming tools and means for feeding the ring-mesh horizontally and vertically in predetermined steps as the formation of the ring-mesh proceeds, the combination of a pattern plate of conductive material, a pattern applied to its surface making it non-conductive for the area of the pattern, a contact pin pressed against the surface of

the pattern, means to cause a relative motion between said pin and said pattern plate corresponding to the motion of the ring mesh with relation to ring forming tools, an electric circuit traversing the said pattern plate, a movable wire guide for a plurality of wires and means to actuate the said movable wire guide by closing and breaking the circuit by the pattern on the pattern plate.

3. In a ring-mesh machine as specified in claim two a pattern plate located below the machine table, a contact pin pressed against the surface of the pattern plate, and means transmitting the lengthwise motion and the vertical motion of the ring mesh to the pattern plate and contact pin.

4. In a ring mesh machine including ring forming tools, means for feeding the ring mesh horizontally and vertically in predetermined steps as the formation of the ring mesh proceeds in combination, and means to feed a plurality of wires to said ring forming tools, the combination of a pattern plate of conductive material having a pattern applied to its surface making the same non-conductive for the area of the pattern, an electric contact member adapted to contact with said pattern, said pattern and said contact member being relatively movable, a connection between the means for moving the ring mesh in the horizontal direction and the said movable member to move said movable member in accordance with the horizontal feed of the ring mesh and a second connection with the vertical feeding means and said movable member to move the movable member in accordance with the vertical feed of the ring mesh.

Signed at Frankfort-on-the-Main, this 25th day of September, 1923.

JOHANN MARTIN WEBER.
